UNITED STATES PATENT OFFICE.

CALVIN B. PATCH, OF GLENELLYN, ILLINOIS, ASSIGNOR TO WILLIAM H. MINER, OF CHAZY, NEW YORK.

KEYLESS YOKE.

1,242,851.

Specification of Letters Patent. Patented Oct. 9, 1917.

Application filed April 13, 1916, Serial No. 90,846. Renewed August 27, 1917. Serial No. 188,493.

To all whom it may concern:

Be it known that I, CALVIN B. PATCH, a citizen of the United States, residing at Glenellyn, in the county of Dupage and 5 State of Illinois, have invented a certain new and useful Improvement in Keyless Yokes, of which the following is a full, clear, concise, and exact description, reference being had to the accompanying drawings, forming a part of this specification.

This invention relates to improvements in keyless yokes.

The object of the invention is to provide a draw-bar and yoke connection for draft 15 riggings so arranged that the draw-bar may be disconnected from the yoke without taking down the yoke or disturbing the gear.

Another object of the invention is to provide a draw-bar and yoke connection of the type above indicated which avoids the use 20 of coupler keys and thereby permits the employment of all standard draw-bars whether the same have coupler key slots or not.

25 In the drawing forming a part of this specification, Figure 1 is a part vertical section, part side elevation of a draw-bar and yoke showing my improvements in connection therewith. Fig. 2 is a horizontal sectional view taken substantially on the line 2—2 of Fig. 1, the draw-bar being indicated by dotted lines. Fig. 3 is a front end elevation of the improved yoke. And Figs. 4 and 5 are perspective views of one of the 35 locking blocks and spreader respectively.

In said drawing, 10 denotes a standard draw-bar having upper shoulder 11 and lower shoulder 12. The yoke A is preferably made in the form of a steel casting 40 and comprises an upper arm 13, lower arm 14, rear connecting piece 15, and an integral, hollow, rectangular hood at its forward end. The hood has an upper wall 16, side walls 17—17 and bottom wall 18. The 45 upper wall 16 is provided with an integral, depending shoulder or gib 19 which co-operates with the upper shoulder 11 of the draw-bar. The bottom wall 18 of the hood is offset downwardly from the lower arm 14 a distance corresponding to the depth of the gib 19 so as to permit the draw-bar butt to be lowered sufficiently to clear said gib when the draw-bar is removed, as hereinafter described. The lower wall 18 is provided with 50 a longitudinally extending, centrally lo-

cated slot 20 for the purpose hereinafter described. To detachably lock the draw-bar and yoke together, I provide two locking blocks B—B which are made right and left. Each block B comprises a flat plate portion 60 21 and an upwardly extended shoulder 22 at its front end. Each block B is also beveled along its inner edge as indicated at 23 to co-operate with the correspondingly beveled upper portion 24 of a spreader retaining block C. The latter has a downwardly extended portion 25 which, when the block C is in position, lies between a pair of depending ears 26—26 located on the underside of the lower wall 18. Said ears 26 70 and the portion 25 of the block C are provided with aligned perforations 126 through which are received cotters 27 or other suitable fastening devices. Each of the side walls 17 of the hood is provided with an 75 inwardly extended shoulder 28 on its inner face against which the front ends of the blocks B abut when the latter are in position.

The parts are shown in the drawings in 80 assembled position and in order to disconnect the draw-bar, the cotters 27 are first removed whereupon the spreader C is removed from below. Each of the blocks B may be then shifted laterally toward the 85 center of the hood a sufficient distance to clear the corresponding shoulder or abutment 28 whereupon the blocks B may be withdrawn forwardly through the open end of the hood. As soon as the blocks B are 90 removed, the draw-bar butt can be lowered to clear the gib 19 and then withdrawn, as will be understood. It is believed the method of assembling the parts will be fully understood from the foregoing description. 95

I claim:

1. A cast yoke for railway draft riggings, said yoke having a hood at its forward end provided with means for engaging the top shoulder of a draw-bar, and detachable devices adapted to lock the yoke with the lower shoulder of a draw-bar, said devices including three members, two of which are shouldered and insertible and removable from the front end of the hood and the third 100 insertible and removable from below through a slot in the bottom of the hood.

2. A cast yoke for railway draft riggings, said yoke having a hood at its forward end provided with means for engaging the top 110

shoulder of a draw-bar, and detachable devices adapted to lock the yoke with the lower shoulder of a draw-bar, said devices including three members, two of which are 5 shouldered and insertible and removable from the front end of the hood and the third insertible from below through a slot in the bottom of the hood, said third member being in the form of a spreader and 10 adapted to be positioned between said two shouldered members to thereby maintain the latter in proper position.

3. A yoke for railway draft riggings having a hood at its forward end, said hood 15 being provided with a transversely extending integral gib arranged to engage the upper shoulder of a draw-bar butt, the lower wall of said hood having a slot therein, a pair of shouldered blocks insertible 20 from the front end of said hood, the shoulders of said blocks being adapted to engage the lower shoulder of a draw-bar butt, and a spreader member insertible through said slot and arranged to have the upper portion

thereof fit between said shouldered blocks, 25 the engaging faces of said blocks and spreader member being beveled.

4. A yoke for railway draft riggings having a hood at its forward end, said hood being provided with a transversely extending 30 integral gib arranged to engage the upper shoulder of a draw-bar butt, the lower wall of said hood having a slot therein, a pair of shouldered blocks insertible from the front end of said hood, the shoulders of said blocks being adapted to engage 35 the lower shoulder of a draw-bar butt, and a spreader member insertible through said slot and arranged to have the upper portion thereof fit between said shouldered blocks, the side walls of the hood being provided on their inner faces with abutments 40 with which said blocks engage when the latter are in operative position.

In witness that I claim the foregoing I 45 have hereunto subscribed my name this 17th day of March, 1916.

CALVIN B. PATCH.
